(57) **CLAIM**

The ornamental design for a combined pacifier and teether, as shown and described.

DESCRIPTION

FIG. 1 is a rear top perspective view of a combined pacifier and teether, showing our new design;

FIG. 2 is a front top perspective view of the combined pacifier and teether of FIG. 1;

FIG. 3 is a front view of the combined pacifier and teether of FIG. 1;

FIG. 4 is a rear view of the combined pacifier and teether of FIG. 1;

FIG. 5 is a top view of the combined pacifier and teether of FIG. 1;

FIG. 6 is a bottom view of the combined pacifier and teether of FIG. 1;

FIG. 7 is a right side view of the combined pacifier and teether of FIG. 1; and,

FIG. 8 is a left side view of the combined pacifier and teether of FIG. 1.

The broken lines in the figures illustrate the portions of the design that form no part of the claimed design.

1 Claim, 8 Drawing Sheets
